UNITED STATES PATENT OFFICE.

ARTHUR H. WESTON, OF NEW YORK, N. Y., ASSIGNOR TO THE T. H. SYMINGTON COMPANY, OF ROCHESTER, NEW YORK, A CORPORATION OF MAINE.

DRAFT-RIGGING.

1,234,988.

Specification of Letters Patent. Patented July 31, 1917.

Application filed October 25, 1916. Serial No. 127,685.

To all whom it may concern:

Be it known that I, ARTHUR H. WESTON, a citizen of the United States, residing at New York, in the county of New York and State of New York, have invented certain new and useful Improvements in Draft-Rigging; and I do hereby declare the following to be a full, clear, and exact description of the invention, such as will enable others skilled in the art to which it appertains to make and use the same.

The invention relates to the art of railway draft rigging for railway cars, and more particularly to the means forming the connection between the coupler and yoke.

To this end the main feature of my invention, broadly stated, comprises a head composed of a plurality of parts, which head is adapted to be securely connected to the yoke, without the use of rivets or other like fastening means, and which is also adapted to be connected to the coupler by means of the coupler key. There are other features of the invention, as will more fully appear from the detailed description of the embodiment which has been chosen for the purpose of illustration, when taken in connection with the accompanying drawing wherein,

Figure 1 is a top plan view of the invention, showing the head connected to the yoke.

Fig. 2 is a longitudinal vertical section of Fig. 1, taken on the line 2—2 thereof.

Fig. 3 is a transverse vertical section of Fig. 2, taken on the line 3—3 thereof, and Fig. 4 is a perspective view showing one of the parts of the head.

Throughout the specification and drawing like parts are designated alike.

The numeral 1 designates the head which preferably comprises two counterpart members 2, and since these members are counterparts it will only be necessary to describe one of them. The member 2 may be forged or cast into the desired shape, and comprises a plate or web 3 in which is located the coupler key receiving slot or opening 4. A reinforcing bead or rib 5 is preferably formed upon the outer face of the web 3 and extends around the outer end of the slot or opening 4. Flanges 6 are provided on the web 3, said flanges extending inwardly from the plane of the web on opposite sides of the slot 4. The said flanges being preferably

of varying thickness, the greatest depth being adjacent the forward end 7, each flange tapering rearwardly therefrom as shown. These flanges are provided with lugs or projections 8, the purpose of which will be hereinafter described.

The yoke 9 is of the vertical type and is provided adjacent the open end with portions 10 which may be formed by bending the forward ends of the arms of the yoke 65 rearwardly upon themselves. Each portion 10 is provided with a slot or opening 11.

The manner of assembling the device is as follows: The members 2 of the head 1 are placed opposite each other, and the head 70 is then moved forwardly along the arms of the yoke until the portions 7 of the head are in contact with the portions 12 of the yoke arms, the lugs 8 being received within the slots 11. When the head is in place the 75 portions 10 of the yoke arms, may, and preferably are forced into contact with the adjacent faces of the flanges 6 to hold the head from sliding rearwardly on the yoke.

The many advantages of the device will, 80 it is believed be clearly seen from the foregoing description. It may not, however, be out of place to call particular attention to some of these advantages. The two-part head is composed of two counterpart members, which practically comprise plates having a plurality of bends therein, this construction rendering the manufacture of the parts of the head exceedingly simple and inexpensive. The form of connection between 85 the parts of the head and the yoke while possessing great strength permits of the ready removal and insertion of the parts of the head which is, of course, of great practical importance in the making of repairs, 90 and the method of connection is such that all liability of the spreading of the yoke, which has heretofore been one of great disadvantages, is entirely eliminated.

Having now described my invention, although it is to be understood that the terms used are to be understood in their descriptive and not in their limiting sense, what I claim and desire to secure by Letters Patent is:

1. In combination with a vertical yoke having the forward ends of the arms thereof extending rearwardly, of a head formed of a plurality of parts, said yoke being provided adjacent the ends thereof with means 110

- integral therewith engaging the head to connect the parts of the head, said head serving as means for operatively connecting the coupler to the said yoke.
- 5 2. In combination with a yoke provided at the free ends thereof with rearwardly extending portions, of a two-part head provided with lateral portions, said portions being adapted to extend between the main body of the yoke arms and the said rearwardly extending portions thereof, and means to prevent the lateral separation of the parts of the said head. 30
- 10 3. In combination with a yoke provided at the free ends thereof with rearwardly extending portions, said portions being spaced from the yoke arms, of a two-part head provided with inwardly extending members, said members being adapted to be received 35 between the yoke arms and the rearwardly extending portions thereof, and means formed on said members and engaging the said yoke to prevent the lateral separation of the parts of the said head.
- 15 4. In combination with a yoke, of a two-part head, projections on the arms of the
- 5 2. In combination with a yoke adapted to receive portions of the said head to prevent lateral movement thereof with respect to the yoke, said yoke being further provided with rearwardly extending portions adjacent the free ends of the arms thereof, said portions being adapted to engage the head to prevent the lateral separation of the parts thereof. 30
3. In combination with a vertical yoke, a two-part head, the yoke having a pair of rearwardly extending slotted arms, and lugs on the parts of the said head, said lugs being adapted to be received within the said slots to prevent the lateral separation 40 of the parts of the head.
4. The combination with a yoke, a two-part head, therefor, the said yoke being adapted to engage the parts of the said head to maintain the same against movement with respect to the said yoke, the parts of the head being adapted to interlock with the said yoke to thereby prevent their lateral separation. 45

In testimony whereof I affix my signature. 50

ARTHUR H. WESTON.
